(57) CLAIM

The ornamental design for a spa and pool jet spindle, as shown and described.

DESCRIPTION

FIG. 1 is a top view of a spa and pool jet spindle showing my new design;

FIG. 2 is a side perspective view thereof; and,

FIG. 3 is a side view of one side thereof.

The features shown in broken lines depict environmental subject matter only and form no part of the claimed design.

1 Claim, 2 Drawing Sheets

FIG. 3
